DROP-LEAF TABLE

Frank Giberson, South Lyons, Mich.

Application June 8, 1945, Serial No. 598,294

6 Claims. (Cl. 311—63)

1

This invention relates to drop leaf tables and particularly swinging leg tables.

As heretofore designed, swinging leg drop leaf tables have sufficed for light loads, but have employed structural principles not compatible with sturdiness. Also difficulty has been experienced in establishing an accurately vertical relation of the legs due to multiplication of any slight inaccuracy in installing the pivotal ends of the leg-mounting, swinging arms. Provision has further been lacking for positively retaining the legs in their outwardly swung positions.

An object of the invention is to so mount and guide the swinging leg-carrying arms of a drop leaf table as to assure considerably greater strength than permitted by prior practice.

Another object is to provide an adjustment for the pivots of the swinging arms, permitting the pivotal axes to be disposed accurately vertical in the course of assembly.

A further object is to provide in a simple manner for locking the legs in their expanded position, thus safeguarding the drop leaves against accidental collapse and substantially assuring that a full expansion of the legs will be utilized.

These and various other objects are obtained by the construction hereinafter described and illustrated in the accompanying drawings, wherein:

Fig. 1 is a bottom plan view of the improved table with its legs outwardly swung.

Fig. 2 is a similar view of the table, with its legs inwardly swung.

Fig. 3 is an end elevational view of the table with its leaves dropped.

Fig. 4 is a fragmentary cross sectional view taken on the line 4—4 of Fig. 1.

Fig. 5 is a fragmentary bottom view of an adjustable bushing mounting one of the arm pivot pins.

Fig. 6 is a fragmentary vertical section taken on the line 6—6 of Fig. 1, showing a wedge-like abutment, one of which holds each arm in expanded position.

Fig. 7 is a perspective view of one of the legs and its supporting arm.

In these views, the reference character 1 designates the fixed center leaf of my improved table and 2 a pair of drop leaves hinged at 3 to opposite margins of the center leaf. Mounted on and downwardly spaced from the mid portion of the leaf 1 is an elongated horizontal board 4 held rigidly in place by four spacer blocks. Lateral margins of the board are secured by screws 5 to a pair 6 of said blocks and the ends of the

2

board are similarly secured to the other opposed pair 7 of the blocks. A rigid mounting of the blocks on the leaf 1 may be effected by glue or any equivalent fastening means. The blocks 6 and 7 are sufficiently spaced apart to afford a desired swinging of four arms 8 closely fitted between the leaf 1 and board 4, the outer ends of said arms rigidly carrying legs 9. The inner ends of the arms 8 rigidly carry vertical pivot pins 10 preferably press-fitted in drilled openings of the arms. These pins project adequately above and below the arms 8 to be journaled in upper and lower bushings 11 and 12 rigidly set into the leaf 1 and board 4 and secured in place by screws 13. It is highly desirable that these pins be perfectly vertical since each leg is definitely parallel to the corresponding pivot pin and any slight tilting of the pins will result in a conspicuous incline of the legs, due to the much greater length of the latter. It is difficult to so set the bushings 11 and 12 into the members 1 and 4 as to assure perfect vertical alignment of the bushing sockets, since said members will be formed in most instances of wood, which does not lend itself to high accuracy. It is preferred, therefore, to locate the sockets of the lower bushings 12 in a slightly eccentric relation to said bushings, as seen in Fig. 5, so that a rotative adjustment of these bushings may serve to correct any slight lack of vertical alignment of the upper and lower sockets before the screws 13 are applied.

When the arms 8 are swung to engage the blocks 7, as illustrated in Fig. 2, this establishes a location of the legs beneath the corner portions of the center leaf 1, strongly supporting the latter while permitting the leaves 2 to drop. It is preferred to bevel the end faces of the blocks 7 to exactly conform to the contiguous arms. When the arms 8 are in their outwardly swung positions (Fig. 1) of engagement with the blocks 6, the legs are positioned to strongly support the leaves 2 in their raised positions, said arms also then having considerable supporting contact with the leaves 2. The ends of the blocks 6 are beveled more acutely than the blocks 7 to conform to the more acute inclinations of the arms, when outwardly swung.

It is desirable to restrain the arms 8 from accidental inward swinging when supporting the drop leaves, as otherwise said arms may yield to pressure inadvertently applied to the legs, causing the drop leaves to either collapse or receive inadequate support. To lock the arms against such yielding, two wedge-like stops 14 are so se-

cured to the bottom face of each leaf 2 that the arms ride under such stops in approaching the blocks 6, clearing such stops at the moment of engagement of the arms with said blocks. The leaves 2 may be held sufficiently raised in outwardly swinging the arms to allow the arms to pass the stops 14 or may rest on the arms as the latter are swung, the wedge shape of the stops adapting them to raise the leaves slightly. When the leaves drop or are dropped to their use positions upon engagement of the arms with the blocks 6, the arms are firmly locked between said blocks and the stops.

It will be observed that the blocks 6 and 7 serve a dual purpose in strongly and rigidly supporting the board 4, while limiting outward and inward swinging of the arms. Said board also serves a dual purpose in accurately guiding the arms in their swinging travel and further mounting the pivot pins 10. It is of vital importance that the board 4 has a considerable outward extent beyond the pivot pins, since this permits confining a considerable length of the arms between said board and the leaf 1. Without this provision a load on the table would entail shearing stresses on the pins 10 acting under a leverage determined by the length of the arms, and the table would be safe only for light loads.

What I claim is:

1. In a drop leaf table, a fixed leaf, a drop leaf, means hinging the drop leaf to the fixed leaf, supporting legs for the table, a pair of swinging arms each rigidly carrying one of said legs, a guide for said arms downwardly spaced from the center portion of the fixed leaf, pivots for said arms jointly mounted in the fixed leaf and guide, the arms being fitted between the fixed leaf and guide, and a support for the guide interposed between the fixed leaf and guide and limiting swinging of both arms.

2. In a drop leaf table, a fixed leaf, a drop leaf, means hinging the drop leaf to the fixed leaf, supporting legs for the table, a pair of swinging arms each rigidly carrying one of said legs, a guide for said arms downwardly spaced from the center portion of the fixed leaf, pivots for said arms jointly mounted in the fixed leaf and guide, the arms being fitted between the fixed leaf and guide, a support for the guide carried between said arms by the fixed leaf and limiting outward swinging of the arms, and two additional supports for the guide carried by the fixed leaf and spaced laterally from the first-mentioned support to respectively limit inward swinging of the respective arms.

3. In a drop leaf table, a fixed leaf, a pair of drop leaves, means hinging the drop leaves to opposite margins of the fixed leaf, a guide downwardly spaced from the center portion of the fixed leaf, four relatively spaced supports for the guide carried by the fixed leaf, four swinging

arms guided between the fixed leaf and guide and outwardly projecting respectively through the four spaces between said supports and limited in their inward and outward swinging by said supports, a leg fixed on the outer end of each arm, and pivots for said arms jointly mounted in the fixed leaf and center portion of the guide and spaced inwardly from said supports.

4. In a drop leaf table, a fixed leaf, a drop leaf, means hinging the drop leaf to the fixed leaf, supporting legs for the table, a pair of swinging arms each rigidly carrying one of said legs, a guide for said arms downwardly spaced from the center portion of the fixed leaf, pivots for said arms jointly mounted in the fixed leaf and guide, the arms being fitted between the fixed leaf and guide, a support for the guide carried between said arms by the fixed leaf and limiting outward swinging of the arms, and stops secured to the bottom face of the drop leaf and engageable with the outwardly swung arms to restrain them from inward swinging, whereby the arms are locked in their outwardly swung positions between said stops and said support, said hinged means affording an upward disengagement of the stops from said arms for the purpose of swinging the arms inward.

5. A drop leaf table as set forth in claim 4, said stops having a wedge shape such that they present inclined faces to the arms as the latter swing out and present approximately vertical faces to the arms in their maximum outward positions.

6. In a drop leaf table, a fixed leaf, a drop leaf, means hinging the drop leaf to the fixed leaf, supporting legs for the table, a pair of swinging arms each rigidly carrying one of said legs, a guide board for said arms downwardly spaced from and parallel to said fixed leaf, pivots for said arms jointly mounted in the mid portion of said board and the fixed leaf, the arms being fitted between the fixed leaf and board, and supports for said board, additionally forming stops limiting swinging of the arms, said supports being interposed between the margin of the board and the fixed leaf.
